ELECTROLYTIC APPARATUS FOR THE RECOVERY OF RARE REFRAC-**TORY METALS**

Norman C. Beese, Verona, and John W. Marden, East Orange, N. J., assignors to the United States of America as represented by the United States Atomic Energy Commission

Application February 7, 1944, Serial No. 521,410

2 Claims. (Cl. 204—245)

This invention relates to an apparatus for recovering rare refractory metals and more particularly to improvements in an apparatus for recovering rare refractory metals, such as uranium, by electrolysis from a fused salt bath.

The electrolytic recovery of uranium powder is disclosed in copending application Serial Number 478,270, filed March 6, 1943, by William C. Lilliendahl et al., now United States Letters Patent No. 2,690,421, issued September 28, 1954. Briefly, the method disclosed in said application includes the preparation of uranium halides, such as KUF_5 , the electrolysis of such halides in a fused bath of calcium and sodium chlorides, whereby uranium in the form of powder is deposited on a cathode, and then the refining of said powder. The present invention relates to improved methods and apparatus for introducing rare refractory metal halides, such as uranium halides known as green salts, into the electrolysis bath for effecting the recovery of purer metal by electrolysis.

Green salts, as they are prepared for example by the methods of said copending application contain small amounts of impurities such as boron, probably in the form of boron oxide, B_2O_3 . The presence of boron as an impurity in electrolytic uranium is particularly undesirable even in small quantities as it alters the properties of the uranium metal and increases the difficulties inherent in using uranium.

The present invention provides a method of substantially eliminating boron and similar impurities from the electrolysis bath, and hence a method which avoids their inclusion in an electrolytically deposited rare refractory metal powder. Briefly, the stated difficulties may be overcome by introducing the salts into the fused salt electrolyte at points of substantially no electrical field and remote from the cathode on which the rare refractory metal is to be deposited. By inserting a suitable anode shield in the electrolyte, points substantially free of electrical fields are provided where the rare refractory metal salt can be heated and impurities therein converted to volatile substances and substantially all of these substances vaporized from the bath before having an opportunity to come in contact with the metal deposited on the cathode.

It is the object of this invention to provide a method of recovering electrolytic rare refractory metals relatively free of impurities such as boron.

It is another object of the invention to provide a method of adding green salt to fused salt electrolytes wherein certain impurities such as boron oxide will be converted to and liberated as vaporized compounds or products without contaminating the uranium electro-

deposited from said bath.

It is another object of this invention to provide a method of continuously adding green salt to a fused electrolyte at points outside of the electric field of said electrolyte in order that at least some of the impurities in the salt may be liberated as vapors or gases without being deposited on the cathode.

It is a further object of the invention to provide an improved apparatus for adding rare refractory metal salts to a fused electrolyte at points remote from the vicinity of a cathode in said electrolyte.

It is another object of this invention to provide apparatus to prevent salts added to a fused electrolyte from entering the electric field in said electrolyte immediately upon contact with the electrolyte.

Other objects and advantages of the invention will be 10 readily apparent to those skilled in the art upon reference to the following description of a preferred method of electrolysis, and to the accompanying drawings showing preferred apparatus embodying our invention.

Fig. 1 of the drawings is an elevation view partly in section of the upper portion of an electrolysis cell and apparatus for feeding green salt thereto. Fig. 2 is a plan sectional view of part of the apparatus of Fig. 1, taken on line 2—2 of Fig. 1.

An electrolysis cell is indicated by the numeral 10. The cell 10, of which only the upper portion is shown, may be a carbon crucible about nine inches inside diameter and twenty-one inches deep, and is connected as an anode in the electrolysis circuit. A number of such cells may be connected in parallel for the quantity production 20 of rare refractory metals, such as uranium, as will be well understood by those skilled in the art. An electrode 11, which serves as a cathode, is positioned at approximately the center of the cell 10 and may be of any suitable shape and material, and supported by conventional means not shown. The cell 10 contains a fused salt bath 12, such as a mixture of calcium chloride and a sodium chloride, substantially filling the cell but having its surface 13 somewhat below the top of the cell. A graphite ring or shield 14 is supported in the 25 upper portion of the cell 10 by means of a plurality of brackets 15 extending between the ring 14 and the upper edge of cell 10. The brackets 15 should be of conducting material and serve to maintain the ring or shield 14 spaced from and at the same potential as the cell 10.

The green salt feeding device includes a housing 16 connected to a conventional form of positive feeding apparatus, and a plurality of feeding tubes 17 extending from the housing 16 into the annular space between the top of the cell 10 and the graphite ring 14, as shown in Fig. 1. The outlet ends 18 of tubes 17 may be above the electrolyte surface 13 as shown, or may extend slightly below the surface. The green salt feeding device 30 may be similar to that shown in the copending application, Serial Number 521,409, filed February 7, 1944, by Norman C. Beese, one of the joint inventors of the present invention, said application having been abandoned.

The method and operation of our present invention resides in continuously feeding rare refractory metal salts into a fused salt electrolyte at points remote from the cathode, and at points at which the electrical field in the fused electrolyte is negligible. For the recovery of uranium, the green salt may be continuously fed into housing 16 by a conveyor of the type illustrated in said copending application of Beese. The green salt in housing 16 is conducted through tubes 17 to outlet ends 18 between the shield 14 and the upper edge of the cell 10. The shield 14 is maintained at substantially the same potential as the cell 10 by means of the supporting brackets 15 of conducting material. The green salt material therefore enters the fused salt electrolyte 12 at 40 points between the shield 14 and the cell 10 at which points the electrical field of the fused electrolyte is negligible. This fact permits the green salt to be heated to the temperature of the electrolyte 12 quickly and causes at least some of the vaporizable impurities therein to be liberated before a migration of ions due to the applied voltage causes the impurities to reach cathode 11 for 45

deposit thereon. It is believed that undesirable impurities, such as boron oxide, B_2O_3 , are converted to halides, such as boron halides, which vaporize at temperatures below the temperature of the fused salt electrolyte which is maintained at about $950^{\circ} C.$, and are liberated from the electrolyte. As the impurities in green salt introduced at the periphery of the electrolyte have a relatively long distance to migrate to reach the centrally positioned cathode 11, the percentage of vaporizable impurities remaining unvaporized and available for deposit on the cathode is relatively small. The introduction of green salt continuously likewise improves the quality of the electrodeposit of uranium on cathode 11, since there are no sudden additions of large quantities of green salt to the electrolyte and consequently the composition of the fused bath can be maintained nearly constant and the impurities have ample time for conversion to vaporized products and liberation as vapors or gases.

The uranium electrodeposited on electrodes in accordance with our improved methods and apparatus is of increased purity in that the boron content drops from several parts per million to little or no boron content in the deposited metal. Some of the elimination of the boron impurity apparently takes place in a space free of electrical fields before electrolysis begins. By retarding the electrolysis until after some of the boron compounds have been converted to vaporizable products and liberated from the electrolyte as vapors or gases, rare refractory metal of high purity and very low in boron content is more readily obtained.

It will be readily apparent that numerous modifications and variations may be made in the above described methods and apparatus within the scope and spirit of our invention as defined in the following claims.

We claim:

1. In apparatus for recovering a rare refractory metal by electrolysis, the combination comprising a crucible for containing a fused electrolyte, said crucible forming the anode of an electrolysis cell, a cathode electrode supported from above and extending into said crucible centrally thereof, and an electrically conducting shield positioned between the inner wall of said crucible and

said electrode, said shield being electrically connected to said crucible to provide a space of substantially no electrical field between said shield and said crucible wall.

2. In apparatus for recovering uranium metal by electrodeposition from a fused electrolyte, the combination comprising a crucible for containing said electrolyte, said crucible having a circular cross section and forming the anode of an electrolysis cell, a cathode electrode supported from above and extending into said crucible at the center thereof, an annular conducting shield extending into said crucible and surrounding said electrode, means extending radially of the crucible between said shield and a wall of said crucible for spacing the shield from and electrically connecting the shield to said crucible, and means for feeding a metal salt to the electrolyte in said crucible at points between the said shield and said crucible.
